WATCHMAN'S CLOCK.

1,387,178.

Specification of Letters Patent.

Patented Aug. 9, 1921.

Application filed October 22, 1919. Serial No. 332,396.

To all whom it may concern:

Be it known that we, THOMAS A. RENDLE and ALOIS BEYER, citizens of the United States, residing at Chicago, in the county of Cook and State of Illinois, have invented a certain new and useful Improvement in Watchmen's Clocks, of which the following is a full, clear, concise, and exact description, reference being had to the accompanying drawings, forming a part of this specification.

Our invention relates to improvements in watchmen's clocks of the type adapted for making a record upon a record receiving dial or disk, and has for one of its objects, the provision of improved mechanism for carrying out the recording operation.

Devices of this type usually include a record receiving dial, clock mechanism for advancing the dial, and a key or recording element arranged for making a record on the dial. In the common form of watchmen's clocks of this type, it has been the practice to provide a key operating element, which when actuated moves the key toward and against the dial with a comparatively slow movement. It is one of the objects of the present invention to provide a recording key operating mechanism, which when actuated, causes the key to strike the dial with a hammer blow, as distinguished from the pushing movement heretofore employed.

A further object resides in the provision of simple, efficient and easily manufactured mechanism for operating and guiding the key.

Another object is the provision of improved mechanism for making a record on the dial whenever the clock casing is opened. Our invention also provides an improved construction whereby the character carried by the key is protected from injury.

These and other objects of the present invention will be pointed out in detail in connection with the accompanying drawings, wherein

Figure 1 is a front elevational view of the watchman's clock of our invention, some of the parts being broken away to reveal more clearly the interior construction of the clock;

Fig. 2 is a vertical cross sectional view taken along the line 2—2 of Fig. 1, looking in the direction indicated by the arrows;

Fig. 3 is a fragmentary cross sectional view taken along the line 3—3 of Fig. 1, looking in the direction indicated by the arrows;

Fig. 4 is a view similar to Fig. 3, showing the locking lever in its open position.

Fig. 5 is a fragmentary cross sectional view taken along the line 5—5 of Fig. 1, looking in the direction indicated by the arrows;

Fig. 6 is a view similar to Fig. 5, showing the key operating mechanism in its advanced or actuated position.

Fig. 7 is a perspective view of the recording key;

Fig. 8 is an enlarged detail view of the shutter mechanism normally interposed between the keyway and the dial;

Fig. 9 is a view similar to Fig. 8, showing the shutter mechanism in its open position;

Fig. 10 is a horizontal cross sectional view taken along the line 10—10 of Fig. 1 looking in the direction indicated by the arrows;

Fig. 11 is a view similar to Fig. 10, showing the inner offset portion of the recording key in the key-guide;

Fig. 12 is a view similar to Fig. 5, showing a modified form of key operating mechanism, and

Fig. 13 is a view similar to Fig. 12, showing the key operating mechanism in its advanced or actuated position.

Similar characters of reference refer to similar parts throughout the several views.

Referring first to Figs. 1 and 2, 14 designates a clock casing, within which is mounted the clock mechanism 15 including the dial 16 and the coöperating hands 17. The back of the casing 14 is open and arranged to be closed by the hinged back shown at 18.

Extending rearwardly from the clock mechanism 15 is a dial operating shaft 19 coöperating with a clamping cap 20 for advancing the dial 21. The upper end of the dial, as shown in Fig. 2, extends into the space 22 formed in the recording mechanism shown at 23. This recording mechanism includes a casting 24 and a plate 25, the latter being fixed to the casting and spaced therefrom, as shown in Fig. 2, to provide the opening into which the dial extends. Extending vertically through the casting 24, and through a collar 26 attached to the cas-

ing, is a key-way 27 arranged to receive a key 28 of the shape shown in Fig. 7. The key 28 comprises the shank 29 and offset portion 30, carrying the type or printing character 31. Extending upwardly from the offset portion 30, and above the type 31, are two lugs 32 and 33, which prevent injury to the type 31 when the key is jarred against some hard substance. Extending longitudinally along the shank 29 is a groove 34 arranged when inserted into the key operating mechanism shown in Figs. 5 and 6 to receive the plate 35 forming part of the lever 36, pivoted at 37 to the casting 24. The free end 10 of the lever 36 is hooked as shown at 38 to embrace the side of the key opposite the slot 34. Extending over the free end of the lever 36 is a second lever 39 pivoted to the casting 24 as shown at 40. Pivoted 15 connected to the lever 39, intermediate its ends, is a plunger 41 provided with a groove 42 arranged for coöperation with a spring pressed detent 43. The upper end of the plunger 41 extends through the front of the clock 20 casing and carries a finger-piece 44 arranged to be pressed by the operator in the recording operation of the key. The plate 25 carries the several depressions shown at 45, which correspond with the type 31 carried 25 by the several keys which are used with the clock. The plate 25 is also provided with the two comparatively deep depressions 46—46 arranged to receive the protecting lugs 32 and 33 of the key.

Pivoted at 47 to the casting 24, as is most 30 clearly shown in Fig. 8, is a shutter operating lever 48 carrying an extension 49 normally extending into the key-way 27. Extending upwardly from the lever 48 is a 35 lug 50 extending into a slot 51 formed in a shutter plate 52 shown in dotted lines in Figs. 8 and 9. The shutter plate 52 is arranged for movement in the guideways shown at 53 and 54. A spring 55 acting between the lever 48 and the casting 24 serves 40 to hold the shutter mechanism in the position shown in Fig. 8. The shutter 52 is normally interposed between the key-way 27 and the dial 21, and cannot be moved to the 45 position shown in Fig. 9, except by the insertion of a proper key.

The operation of the mechanism thus far described is as follows:

A key of the type shown in Fig. 7 is 50 inserted into the key-way 27, and as the offset portion 30 of the key engages the extension 49 of the lever 48, the lever is moved in a clockwise direction, as shown in Figs. 8 and 9, and the shutter plate 52 moved 55 away from the key-way as shown in Fig. 9. When the key is in this position, the offset portion 30 thereof is in alignment with the depressions 45 in the plate 25, the reduced shank 29 lying to the right side of the 60 key-way 27. (See Fig. 2.) There is then a

certain amount of space to the left of the shank so that the key may be moved by the actuating lever 36 toward the plate 25. The operator presses downwardly on the thumb-piece 44, the pressure being increased until 70 the resistance of the spring detent mechanism 43 is overcome, with the result that the levers 39 and 36 are suddenly snapped inwardly. Due to the connection between the key and the lever 36, as most clearly 75 shown in Fig. 5, the key is moved toward and against the dial with a hammer blow, and the type 31 carried by the key is caused to make an impression on the dial. The pressure is then relieved from the thumb-piece 44 and the spring 56 permitted to return the parts to their normal positions. If desired, the collar 26 containing the key guideway may be provided with a lug 57 arranged to coöperate with the groove 34 80 in the key, the groove in the key being enlarged at 58 to permit free movement of the key after it has been inserted into the recording mechanism. This arrangement prevents the use of any keys except those which 85 are intended to be used with the clock.

Referring now to the construction shown in Figs. 3 and 4, 59 designates a hook extending inwardly from the hinged cover 18. Arranged to coöperate with this hook is a 95 locking lever 60 pivoted at 61 to the clock casing. The lever 60 includes an arm 62 which carries a knife 63 arranged when the lever is moved in a clockwise direction, as shown in Figs. 3 and 4, to pass through the 100 dial. The inner or operating end of the lever 60 extends into a cam slot 64 formed in the gear rack 65. The gear rack 65 co-operates with a pinion 66, in turn operated by a suitable key inserted in the key-guide 105 shown at 67. In the operation of this mechanism, the key is inserted in the key-guide 67 and given a counter-clockwise rotation, (Fig. 1). Due to the coöperation of the gear rack and pinion, the rack 65 is moved 110 downwardly as shown in Fig. 1 and the operating end of the lever 60 is swung in a clockwise direction as shown in Figs. 3 and 4. This movement of the lever results in a releasal of the hook member 59 and the 115 cutting action of the knife 63 carried by the lever.

In the modified arrangement shown in Figs. 12 and 13, the plunger 41^a is provided with the groove 70, into which extends a pin 71 carried by the finger-piece 72. This permits the finger-piece 72 to have certain longitudinal movement relatively to the plunger 41^a. Interposed between the finger-piece 72 and the plunger 120 41^a is a coil compression spring 73 normally holding the parts in the position shown in Fig. 12. In the operation of this device, the finger-piece 72 is pressed downwardly until enough pressure is stored in 125 130

the spring 73 to overcome the resistance offered by the spring detent 43^a. The spring 73 then serves to move the recording key against the dial as shown in Fig. 13. This arrangement does not necessitate further movement of the finger-piece 72 after the detent 43^a releases the plunger.

Having thus described my invention, what I claim as new and desire to secure by Letters Patent of the United States is:

1. In a watchman's clock the combination of a casing, a record receiving means therein, a recording element for making a record thereon, and devices for striking the recording element against the record receiving means, said devices comprising a pivoted recording element carrier, a finger-piece, a spring interposed between the finger-piece and carrier arranged to store energy applied to the finger-piece, and a resistance member preventing operation of the carrier until a certain predetermined amount of energy has been stored in the spring.

2. Recording mechanism for watchmen's clocks comprising a support, a key-carrier pivoted to the support, a lever pivoted to the support and having its free end extending over the key-carrier for operating the latter, a plunger connected with said lever, a finger-piece on the plunger and a detent between the support and plunger for resisting the initial movement of the plunger.

3. Recording mechanism for watchman's clocks comprising a casing, a support therein, a key carrier in said support, a lever for moving said carrier, means for actuating

said lever, and a detent for resisting the initial movement of said means.

4. Recording mechanism for watchman's clocks comprising a casing, a support, a key carrier pivoted to said support, means for actuating said carrier and a detent for resisting the initial movement of said means.

5. Recording mechanism for watchman's clocks comprising a support having a key-way therein, a platen, a shutter normally extending over the keyway between said keyway and platen, a lever normally extending into said keyway for operating said shutter, a recording key adapted to be received in said keyway, said key having printing characters thereon arranged to be received in said platen and lugs on said key adjacent said printing characters.

6. Recording mechanism for watchman's clocks comprising a support having a key-way therein, a platen, a shutter normally extending over the keyway between said keyway and platen, a recording key arranged to be received in said keyway, type characters on said key for coöperating with said platen, and lugs on said key for operating said shutter and for protecting said type characters substantially as described.

In witness whereof, we hereunto subscribe our names this 9th day of October, 1919.
